UNITED STATES PATENT OFFICE.

JOHN A. COLE, OF CHICAGO, ILLINOIS.

ROD METER.

Application filed December 20, 1923. Serial No. 681,898.

To all whom it may concern:

Be it known that I, JOHN A. COLE, a citizen of the United States, residing at Chicago, in the county of Cook and State 5 of Illinois, have invented a certain new and useful Improvement in Rod Meters, of which the following is a full, clear, concise, and exact description, reference being had to the accompanying drawings, forming a part 10 of this specification.

My invention relates to rod meters, particularly adapted for making Pitot tube connections with water pipes.

One of the objects of the invention is to 15 provide a simple, practical and efficient rod meter of this class.

Another object of the invention is to accommodate the pressure of the water in the pipe so that it may be free and undue 20 friction may be avoided.

Another object of the invention is to arrange for the turning of the tube connections so that either one or both may be turned independently to facilitate and improve 25 couplings and connections.

In the accompanying drawings Fig. 1 is a vertical section of a rod meter embodying my present invention inserted in a water pipe ready for use;

Fig. 2 is a vertical section of a portion 30 of the device;

Figs. 3 and 4 are cross sections on lines 3—3 and 4—4, respectively, in Fig. 1.

Referring to the drawings, I show a water 35 pipe 1 and a rod meter 2 embodying my present invention, the end of the rod meter being introduced into water pipe 1 and held there by means of a block 3 having a screw threaded connection with the water pipe 1.

The rod meter 2 is conveniently composed 40 of a tubular sheath 4 containing tubes 5—5, said sheath 4 being more or less oblong in shape, as shown in Fig. 4, and the tubes or pipes 5—5 being at the opposite ends of 45 the same. Said tubes or pipes 5—5 are loose in the sheath so that they may be turned, that is rotated about their axes, and each tube may be turned or rotated independently. Stuffing boxes 6—6 are preferably 50 provided to make the sheath 4 water and air tight, the tubes 5—5 being removable and rotatable, however, in said stuffing boxes 6—6. Each tube 5—5 is preferably provided with a bent end 7—7 by which it 55 may be readily grasped and turned, and also

by which tube connection may be readily made.

The sheath 4 is preferably provided with apertures 8 and 8^a, desirably located at or near its lower end, one aperture as 8 facing up stream, and the other aperture 8^a facing down stream. The tubes or pipes 5—5 extend well down toward the bottom of the sheath 4, but are preferably prevented from extending clear down to the same or to the 60 apertures 8 and 8^a, and to such end stops or abutments 9—9 are desirably provided, against which stops the tubes 5—5 will strike when they have been lowered a predetermined distance, as shown for example, 65 in Fig. 1.

A central member 11 is located between tubes or pipes 5, 5, forming inner guides for the same and also forming a partition dividing the lower part of interior of sheath into 70 two chambers 10, 10, communicating with orifices 8 and 8^a respectively. These chambers 10, 10, being below the ends of the tubes or pipes and in the lower end of the sheath 4 permits the water to enter apertures 8 and 8^a and then pass through chambers 10, 10, and into tubes 5, 5, and furthermore the tubes 5—5 may be pushed down as far as possible by hand without any likelihood 80 of trouble or interfering with the water circulation, and so provision is made for the ready rotation and proper accommodation 85 of these tubes.

It will be understood that changes and modifications may be made without departing from the spirit of the invention.

What I claim is:

1. A rod meter having a sheath having its lower portion provided with up and down stream orifices, a partition in the lower 95 portion of said sheath dividing said lower portion into separate chambers communicating with said orifices, tubes insertable into said sheath, and stop devices for preventing the downward movement of said tubes below 100 predetermined points.

2. A rod meter comprising a tubular sheath having its lower end provided with up and down stream orifices, a partition in the lower part of said sheath dividing same 105 into separate chambers communicating with said orifices and a pair of tubes arranged in said sheath and extending down nearly to said orifices.

3. A rod meter comprising a tubular 110

sheath having its lower end provided with up and down stream orifices, a partition dividing said sheath into separate chambers communicating with said orifices and a pair 5 of tubes insertable into said sheath and extending down nearly to said orifices, and projections extending inwardly in said sheath and forming stops for the lower ends of said tubes.

10 4. A rod meter comprising a tubular sheath having one end provided with up and down stream orifices, a partition dividing that part of the interior of said sheath with which said orifices communicate into

two chambers so that one orifice communicates with one chamber and the other orifice with the other chamber, and tubular members insertable into and removable from said sheath and communicating respectively with said chamber, said partition comprising a central member located between said tubular members and forming inner guides for the same.

In witness whereof, I hereunto subscribe my name this 13th day of December, A. D. 25 1923.

JOHN A. COLE
